(57) **CLAIM**

The ornamental design for a probe head, as shown and described.

DESCRIPTION

FIG. 1 is a top view of a probe head according to the present invention;

FIG. 2 is a front view of the probe head of FIG. 1;
FIG. 3 is a left view of the probe head of FIG. 1;
FIG. 4 is a back view of the probe head of FIG. 1;
FIG. 5 is a right view of the probe head of FIG. 1;
FIG. 6 is a bottom view of the probe head FIG. 1;
FIG. 7 is a top-left rear view of the probe head of FIG. 1;
FIG. 8 is a top-right rear view of the probe head of FIG. 1.
FIG. 9 is a top-left front view of the probe head of FIG. 1.
FIG. 10 is a top-right front view of the probe head of FIG. 1.
FIG. 11 is a bottom-right front view of the probe head of FIG. 1.
FIG. 12 is a bottom-left front view of the probe head of FIG. 1.
FIG. 13 is a bottom-left rear view of the probe head of FIG. 1; and,
FIG. 14 is a bottom-right rear view of the probe head of FIG. 1.
